J. F. WILKINSON,
PROGRESSIVE ROCKING HORSE,
APPLICATION FILED APR. 29, 1916.

1,212,122.

Patented Jan. 9, 1917.

UNITED STATES PATENT OFFICE.

JOHN F. WILKINSON, OF WINCHENDON, MASSACHUSETTS, ASSIGNOR TO ARTHUR F. EVANS, TRUSTEE OF THE RUNNING PONY COMPANY, OF WINCHENDON, MASSACHUSETTS.

PROGRESSIVE ROCKING-HORSE.

1,212,122.

Specification of Letters Patent.

Patented Jan. 9, 1917.

Application filed April 29, 1916. Serial No. 94,353.

To all whom it may concern:

Be it known that I, JOHN F. WILKINSON, a citizen of the United States, residing at Winchendon, in the county of Worcester and State of Massachusetts, have invented new and useful Improvements in Progressive Rocking-Horses, of which the following is a specification.

This invention relates to rocking supports for the human body, usually made to resemble an animal, such as a horse, adapted to be rocked or tilted forward and backward by the rider and constructed to move progressively step by step while rocking.

15 The invention is embodied in the herein-after described improvements in a progressively moving rocking horse.

Of the accompanying drawings forming a part of this specification: Figure 1 represents a side view of a rocking horse embodying my invention, tilted backward, a part of the body being broken away; Fig. 2 represents a view similar to Fig. 1, showing the horse at rest; Fig. 3 represents a fragmentary perspective view, showing parts of the front legs and the steering means detached from the base; Figs. 4 and 5 represent fragmentary side views illustrating a different embodiment of the invention; Fig. 30 represents a fragmentary perspective view, showing parts of the front legs and the steering means represented by Figs. 4 and 5; Figs. 7 and 8 represent a portion of one of the rear rockers and the roller mounted thereon.

The same reference characters indicate the same or similar parts in all the views.

Referring to Figs. 1, 2 and 3, the body 12 of the horse is provided with rigid rear legs 13 having rear rockers 14 formed and arranged to support the body in a backwardly tilted position, as shown by Fig. 1. The front legs 15 are pivoted at 16 to the body and are adapted to oscillate toward and from the rear rockers. Said front legs are provided with front rockers 17 formed and arranged to coöperate with the rear rockers in supporting the body at rest, as shown by Fig. 2, said front rockers permitting the body to be tilted forward far enough to raise the rear rockers slightly from the floor. When the body is tilted backward the front rockers are raised from the floor, means being provided as hereinafter described for swinging or projecting the front legs forward, said

means being operative when the body is tilted backward. In this embodiment of the invention the front legs are projected manually by means controlled by the rider, said means including reins 18 arranged to be pulled by the rider, bell crank levers 19 pivoted at 20 to the head of the horse, the reins being connected with two of the arms of said levers, and crossed straps 21 connecting the other arms of the bell crank levers with the front legs 15, the arrangement being such that when both reins are pulled the front legs are projected simultaneously to the position shown by full lines in Fig. 1. When the reins are loose the front legs are retracted by gravity, as indicated by dotted lines in Fig. 1, so that their rockers 17 are normally in position to form extensions of the rear rockers 14, the horse being adapted to rock without moving progressively. When the rider pulls both reins while the horse is tilted backwardly, the front legs are simultaneously projected as indicated by full lines in Fig. 1, the front rockers being spaced forward from the rear rockers. The next forward tilting movement of the horse causes the front rockers to bear on the floor and slightly raises the rear rockers 14 therefrom, thus permitting the body 12 and the rear rockers to swing by gravity on the pivot 16, 85 the rear rockers moving forward toward the front rockers. The body of the horse is thus advanced a short distance on the floor. This operation repeatedly performed causes the horse to move progressively step by step. 90 The front legs are independently movable, so that either may be projected and the other allowed to remain in its normal position, as indicated by full and dotted lines in Fig. 1. Provision is therefore made for guiding or steering the horse, the projected front leg coming to a bearing on the floor at one side of the median line, so that the weight of the horse and rider causes the horse to swerve to one side of said line, the horse pivoting on the rear end of the projected front rocker 17 when said end contacts with the floor.

Figs. 4, 5 and 6 illustrate another embodiment of the invention, in which the independently movable front legs, instead of being normally retracted, are normally projected by springs 25, as indicated by Fig. 4, so that when the body is tilted backward the front legs are automatically caused by springs to assume the position shown by full 110

- lines in Fig. 1. The front legs may be retracted by a pull on the reins through suitable connections between the reins and the front legs, said connections as here shown including levers 26 pivoted at 27 to the head of the horse, and stiff metal rods or struts 28 connecting said levers with the front legs. The reins 18 are connected with the outer ends of the levers 26, and the rods 28 are connected with said levers at points between the inner and outer ends of the latter. When the front legs are projected by the springs 25, the levers stand as shown by Figs. 4 and 6, and when both reins are pulled the levers are moved to the position shown by Fig. 5, thus retracting the legs through the struts 28. A pull on one rein only retracts one leg, leaving the other projected, so that the horse may be steered by tilting it forward while one leg is projected and the other retracted.
- The body 12 and its adjuncts may obviously be formed to represent an animal or object other than a horse.
- The rockers 14 may be provided with rollers 31 constituting antifrictional means arranged to roll upon the floor when the body is tilting forward. As shown by Figs. 7 and 8, said rollers may be mounted on stub axles 30 formed on plates 33 attached to the inner sides of the rear rockers.

The front legs normally held retracted toward the rockers 14 may be projected or swung forward by the feet of the rider either simultaneously, to cause a progressive movement in a straight path, or independently, one at a time, to cause a progressive movement in a curved path. The straps 21 may therefore be omitted and the horse directed wholly by the feet of the rider, instead of being directed manually, without departing from the spirit of the invention.

Having described my invention, I claim:—

1. A progressive rocking horse comprising a body, rigid rear legs provided with rockers, independently movable oscillatory front legs pivoted to the forward portion of the body, the rockers being adapted to support the body backwardly tilted with the front legs raised from the floor, and the front legs being adapted to support the body forwardly tilted with the rockers raised from the floor, and means operative when the body is tilted backward for projecting the front legs either singly or simultaneously to cause a forward movement of the rockers when the body is again tilted forward.

2. A progressive rocking horse comprising a body, rigid rear legs provided with rockers, independently movable oscillatory front legs pivoted to the forward portion of the body, the rockers being adapted to support the body backwardly tilted with the front legs raised from the floor, and the

front legs being adapted to support the body forwardly tilted with the rockers raised from the floor, and means operative when the body is tilted backward for projecting the front legs either singly or simultaneously to cause a forward movement of the rockers when the body is again tilted forward, the front legs being normally held retracted toward the rockers.

3. A progressive rocking horse comprising a body, rigid rear legs provided with rockers, independently movable oscillatory front legs pivoted to the forward portion of the body, the rockers being adapted to support the body backwardly tilted with the front legs raised from the floor, and the front legs being adapted to support the body forwardly tilted with the rockers raised from the floor, and means operative when the body is tilted backward for projecting the front legs either singly or simultaneously to cause a forward movement of the rockers when the body is again tilted forward, the front legs being provided with rockers adapted to coöperate with the rockers on the rear legs.

4. A progressive rocking horse comprising a body, rigid rear legs provided with rockers, oscillatory front legs pivoted to the forward portion of the body, the rockers being adapted to support the body backwardly tilted with the front legs raised from the floor, and the front legs being independently movable, and means controlled by the rider and operative when the body is tilted backward for selectively projecting one leg only and thereby guiding the horse laterally, said means being adapted to simultaneously project both legs and thereby cause a straight ahead movement.

5. A progressive rocking horse comprising a body, rigid rear legs provided with rockers, oscillatory front legs pivoted to the forward portion of the body, the rockers being adapted to support the body backwardly tilted with the front legs raised from the floor, and the front legs being adapted to support the body forwardly tilted with the rockers raised from the floor, the front legs being independently movable, reins arranged to be pulled by the rider, and connections between said reins and the front legs, the arrangement being such that both front legs may be simultaneously projected, or either leg projected alone by said reins.

6. A progressive rocking horse comprising a body, rigid rear legs provided with rockers, oscillatory front legs pivoted to the forward portion of the body, the rockers being adapted to support the body backwardly tilted with the front legs raised from the floor, and the front legs being adapted to

support the body forwardly tilted with the rockers raised from the floor, the front legs being independently movable, reins arranged to be pulled by the rider, a pair of two-
5 armed levers fulcrumed on the head portion of the body and connected with said reins, and connections between said levers and the front legs.

7. A progressive rocking horse comprising a body, rockable supporting means rigidly connected with the rear portion of the body, oscillatory supporting means pivoted to the front portion of the body and composed of a pair of independently movable front legs, each of said supporting means being adapted to support the body with the other supporting means raised from the floor, and means operative when the body is tilted backward for projecting 20 the front legs either singly or simultaneously.

8. A progressive rocking horse comprising a body, rockable supporting means rigidly connected with the rear portion of the body, oscillatory supporting means pivoted to the front portion of the body, each of said supporting means being adapted to support the body with the other supporting means raised from the floor, and 25 means operative when the body is tilted backward for projecting the oscillatory supporting means, said rockable supporting means being provided with antifrictional means arranged to bear on the floor when the body is tilting forward.

9. A progressive dirigible rocking horse comprising a body, rigid rear legs provided with rockers adapted to support the body

backwardly tilted, and independently movable oscillatory front legs pivoted to the forward portion of the body and adapted to support the body forwardly tilted, the front legs being normally held retracted toward the rockers and movable forward by the rider either simultaneously or independently to cause a progressive movement of the horse either in a straight path or a curved path.

10. A progressive rocking horse comprising a body, rockable supporting means rigidly connected with the rear portion of the body, oscillatory supporting means pivoted to the front portion of the body, each of said supporting means being adapted to support the body with the other supporting means raised from the floor, and the oscillatory supporting means being adapted to be swung forward when the body is tilted backward, and antifriction rollers mounted on the rockable supporting means and adapted to bear on the floor when the body is tilted forward.

11. A progressive rocking horse comprising a body, rigid rear legs provided with rockers adapted to support the body backwardly tilted, and oscillatory front legs pivoted to the forward portion of the body and adapted to support the body forwardly tilted, the front legs being normally held retracted yieldingly toward the rockers and movable forward by the rider when the body is tilted backward, to cause a progressive movement of the horse.

In testimony whereof I have affixed my signature.

JOHN F. WILKINSON.
